PULL-CORD KNOB OR SIMILAR ARTICLE

Irving Hartley Steinhardt, New York, N. Y.

Application October 1, 1949, Serial No. 5,247

Term of patent 14 years

(Cl. D48—14)

To all whom it may concern:

Be it known that I, Irving Hartley Steinhardt, a citizen of the United States, residing at New York, in the county of New York and State of New York, have invented a new, original, and ornamental Design for a Pull-Cord Knob or Similar Article, of which the following is a specification, reference being had to the accompanying drawing, forming part thereof.

In the drawing:

Fig. 1 is a side view in elevation of a pull-cord knob showing my new design;

Fig. 2 is a bottom plan view thereof; and

Fig. 3 is a top plan view thereof.

The dotted lines shown in the drawing are for illustrative purposes only.

I claim:

The ornamental design for a pull-cord knob or similar article, substantially as shown and described.

IRVING HARTLEY STEINHARDT.
